UNITED STATES PATENT OFFICE.

GEORGE P. LELY, OF PARKSTONE HEIGHTS, ENGLAND.

CALENDAR OR DATE-INDICATOR.

1,368,168.

Specification of Letters Patent.

Patented Feb. 8, 1921.

Application filed April 29, 1919. Serial No. 293,474.

To all whom it may concern:

Be it known that I, GEORGE PEEL LELY, a subject of His Majesty the King of Great Britain, and resident of Parkstone Heights, 5 in the county of Dorset, Kingdom of England, have invented a certain new and useful Calendar or Date-Indicator, of which the following is a specification.

This invention relates to calendars and 10 has for its object to provide an improved construction of calendar wherein the number of operations required to effect a change in the dates shown by the calendar is reduced to a minimum.

15 According to this invention the calendar essentially comprises two alined or superposed members one bearing an indication of the date of the day of the month and the other the day of the week, the two members 20 being relatively rotatable so as to adjust the day of the week with respect to the day of the month or vice versa and thereafter simultaneously rotatable daily or when desired to indicate the diurnal changes and the 25 corresponding changes in the numbers of the days of the month. The two rotatable members thus retain throughout the month the relative positions to which they or one of them have or has been set at the beginning 30 of the month.

I will describe with reference to the accompanying drawing a construction in accordance with the present invention but I do not limit myself to the precise construction described and illustrated.

Figure 1 is an elevation of a calendar in accordance with the present invention.

Fig. 2 is an elevation of the calendar with the front casing partly broken away.

40 Fig. 3 shows a section of the numerical and diurnal rollers.

Figs. 4 and 5 are elevations of modified forms of the invention and Figs. 6, 7, 8 and 45 9 show respectively an elevation, a section, an elevation and a section of the calendar of Figs. 1 and 5 as applied to a wristlet or watch wristlet.

Referring to Figs. 1 and 2 of the drawings the calendar comprises a wooden, metal or 50 other suitable casing 1 provided adjacent its upper end or one end, with a radially split member forming two alined rollers 2, 3 or with separate alined rollers on one 2 of which are arranged suitable indications of 55 the date of the day of the month, the other roller 3 bearing indications of the days of

the week. The two alined rollers 2, 3 are preferably mounted on the same spindle 4 and are so constructed that relative rotation of the two rollers 2, 3 can be effected in order 60 to alter the day of the week to correspond with the day of the month. This adjustment may be effected in any suitable and convenient manner. One such construction to give the desired result is shown in Fig. 3 65 and consists in providing the end of one roller 2 say the roller carrying the numbers corresponding to the days of the month with a V shaped recess 5, the spindle 4 being provided with a cross pin 6 adapted to engage 70 the said recess. On pulling the spindle 4 outward or pushing the spindle inward by the handle 4' against the action of a spring 7 the other roller being fixed by a pin 8 or set screw 9 to the spindle and rotatable therewith one roller 3 may then be rotated 75 relatively to the roller 2. On releasing the adjusted roller 3, the two rollers engage so that they can be rotated simultaneously.

Fig. 4 shows a construction wherein the 80 numerical indications of the date of the month are indicated on an endless band 10, the diurnal indications being shown as mounted in a separate endless band 11. The two bands 10 and 11 are carried by the rollers 2, 3 as previously described and are supported on a lower and freely rotatable roller 12. The upper rollers 2, 3 can be rotated as previously described with reference to Fig. 1 or the adjacent ends 13, 14 of the alined 85 rollers 2, 3 may be provided with teeth or notches so as to form a clutch device whereby the two rollers can be rotated simultaneously. By pulling the roller 3 relatively to the other roller 2 against the action of 90 the spring 7, the two rollers can be adjusted 95 relatively to each other in the manner hereinbefore described.

In front of the alined rollers 2, 3 is or are arranged an opening or openings 15, 16 in 100 the casing so that the numbers of the days of the month and the diurnal indications may be visible therethrough. Such opening, or openings may be glazed or provided with a transparent cover of celluloid or other 105 suitable material. A similar opening 17 or slot preferably also glazed is arranged in the casing 1 below the former opening or openings and through this opening can be clearly seen an indication of the month, such 110 indication being engraved, stamped, painted or otherwise suitably indicated on the roller

or endless band which roller is capable of being rotated by the handle from outside the casing.

In the modified construction of calendar 5 shown in Fig. 5 the two alined rollers 2, 3 hereinbefore referred to may be employed as separately mounted rollers one above the other, one roller 2 being provided with the numerical indications of the days of the 10 month and the other roller 3 with the diurnal indications. These two superposed rollers are each in this construction provided outside the casing with a gear wheel 18, 19 belt or equivalent pulley so that they 15 can be rotated simultaneously. The spindle of the roller 2 may be provided on one end with a milled or other suitable disk 20 by which the said roller may be rotated relatively to the other roller without however 20 rotating the latter roller. This may be effected by a construction similar to that shown in Fig. 3. The monthly indications are mounted on a roller as in Fig. 1 or on an endless band as in Fig. 4, these being 25 seen through an opening or slot provided in the casing wall such opening or slot being glazed, or provided with a transparent covering if so desired.

Figs. 6 and 7 show respectively a plan 30 and edge view of the calendar as applied to a wristlet or watch wristlet. In this construction the rollers shown in Fig. 1 are mounted in a metal or other suitable casing 21 which is secured to the face of the 35 leather or other wristlet or as shown between the plies 22, 23 thereof. The rollers 24 are rotated relatively by the hand wheel 4' as in Fig. 1 in the manner hereinbefore described and the month indicating roller 40 by the hand wheel or knob 5'. The casing 21 carrying the rollers is secured to the wristlet by rivets 25 or other suitable means.

Figs. 8 and 9 illustrate in plan and edge view the application of the calendar shown 45 in Fig. 5 to a wristlet, 2, 3 being the numerical and diurnal indicating rollers respectively, and 26 the month indicating roller. As in Fig. 6 the casing 21 is secured between the plies 22, 23 of the wristlet, but the casing 21 may be secured to the face of the leather or other material fixing 50 the wristlet if so desired.

If so desired the numerical, diurnal and monthly indications may be indicated on

separate rollers, which may be mounted in 55 alinement. In such construction the month indicating and diurnal indicating rollers may occupy end positions the numerical indicating roller being arranged therebetween. To effect this arrangement the 60 month indicating roller may be supported on a central spindle passing through a tube on which the numerical indicating roller and the diurnal indicating roller are respectively mounted the numerical indicating roller being loose or fixed on the tube and the diurnal roller fixed to the tube. The latter is provided with a milled wheel which extends outside the frame as also 65 the central spindle which extends beyond 70 the tube and outside the frame on either side or on both sides thereof. The month indicating roller may be carried by a spindle secured to and movable with the central spindle. The adjacent edges or faces 75 of the tube carrying the numerical indicating roller and the diurnal roller may be notched so that they can be adjusted independently and thereafter when desired rotated simultaneously, while the month indicating roller may be rotated independently 80 of the other two rollers.

What I claim is:—

1. A calendar comprising a shaft including telescopically related sections, a roller 85 arranged upon each section, and means carried by one shaft section to coöperate with the roller of the other shaft section to fix said rollers as a unit rotatably through movement of the shaft, a movement of one 90 shaft section relative to the other freeing the rollers for independent movement.

2. A calendar comprising an indicating roller made up of endwise alined sections, a shaft on which said roller is mounted 95 comprising telescopically related sections, a transverse pin carried by one shaft section adapted to engage notches formed in the meeting end of one roller section, whereby when said pin is arranged in said notches, 100 the roller sections are secured together, and when the shaft sections are extended to withdraw the pin from the notches, the roller sections are separated for independent movement.

In testimony whereof I have hereunto signed my name.

G. P. LELY.
